UNITED STATES PATENT OFFICE.

SAMUEL J. SEIFRIED, OF CHICAGO, ILLINOIS, ASSIGNOR TO THE MUNSON
TYPE WRITER COMPANY, OF SAME PLACE.

TYPE-WRITING MACHINE.

SPECIFICATION forming part of Letters Patent No. 474,350, dated May 3, 1892.

Application filed August 14, 1891. Serial No. 402,684. (No model.)

To all whom it may concern:

Be it known that I, SAMUEL J. SEIFRIED, a citizen of the United States, residing at Chicago, in the county of Cook and State of Illinois, have invented a new and useful Improvement 5 in Type-Writing Machines, of which the following is a specification.

My invention relates to improvements in type-writers wherein a rotatable sliding type-sleeve is employed, and more particularly to improvements upon the type-writer heretofore patented to me in Letters Patent No. 411,066, of September 17, 1889, and No. 446,394, of February 10, 1891.

15 My improved type-writer has the same general principle and mode of operation as the machine heretofore patented to me in the Letters Patent above named.

The improvements which I have made are 20 designed to simplify the construction of the machine, to render it more durable, its operation more efficient and certain, and to enable it to be more conveniently operated.

In my former machine the paper was wound 25 around a paper holder or cylinder to keep the same out of the way of the hammer and the mechanism for communicating motion to the hammer.

In my present invention the hammer and 30 part of the mechanism for communicating motion thereto are mounted upon a goose-neck frame or support, so that I can pass the sheet of paper around the hammer or between the hammer and the machine proper, thus enabling me to dispense with the paper-storage 35 cylinder or roller, and thus materially diminish the cost of the machine, as well as greatly increasing the convenience of its operation in putting the paper in or out and adjusting 40 the position of the same.

Another feature of my present improvement consists in mounting the goose-neck hammer-supporting frame to telescope or slide upon the main frame of the machine, so 45 that the goose-neck will shut within the latter when the machine is not in use, and thus cause the machine to be as compact as though the goose-neck support for the hammer were not employed.

50 Another feature consists in the means for connecting and disconnecting the hammer-

operating mechanism which is mounted on the goose-neck frame with that which is mounted upon the main frame by the simple act of sliding the goose-neck in or out, so that no inconvenience may arise from the sliding or telescopic connection of the goose-neck with the main frame.

In my present improvement, as will be hereinafter more particularly explained, I have 60 also materially simplified the mechanism for communicating the necessary rotary and sliding movements to the type-sleeve from the key-levers, also the mechanism for supporting and operating the ink-ribbon, and also the 65 general construction of the paper-carriage.

My invention also consists in the novel devices and novel combinations of parts and devices herein shown and described, and more particularly pointed out in the claims.

In the accompanying drawings, which form a part of this specification, and in which similar letters of reference indicate like parts throughout all the figures, Figure 1 is a plan view of a machine embodying my invention. 75 Fig. 2 is a side elevation. Fig. 3 is a vertical section taken on line 3 3 of Fig. 1. Fig. 4 is a vertical section taken on line 4 4 of Fig. 1. Fig. 5 is a detail plan view of the key-levers and their connections. Fig. 6 is a detail side 80 elevation of the key-levers and mechanism for rotating the type-sleeve to change from one case to another. Figs. 7 and 8 are similar views of the same in different positions. Fig. 9 is a detail elevation of the mechanism 85 for communicating the necessary rotary movement to the type-sleeve. Fig. 10 is a detail perspective view of a part hereinafter to be described. Fig. 11 is a detail perspective view of the goose-neck frame or support upon which the hammer is mounted. Fig. 12 is a detail 90 cross-section of the carriage. Fig. 13 is a detail elevation of the mechanism for operating the paper-feed roller. Fig. 14 is a detail section of the escapement mechanism. Fig. 15 is a detail face view of the escapement-wheel. Fig. 16 is a section on line 16 16 of Fig. 7. Fig. 17 is a detail view of the latch for locking the cap-key lever and figure-key lever in place.

In the drawings, A represents the frame of the machine. The frame A is furnished with

rubber feet or cushions A' and with vertical side pieces or wings A², upon which the main shafts of the type-writer are pivoted or journaled. The frame also has front and rear 5 combs or slotted plates A³ and A⁴ to serve as guides for the key-levers.

B B represent the keys, preferably thirty in number, arranged in three transverse rows. B' B² B³ are the key-levers for the three rows 10 of keys, pivoted to shafts b b' b², respectively, and which extend across the frame.

C is the rotary sliding type-sleeve, furnished with an annular groove c near its middle and a spline or projection c', which engages the 15 longitudinal groove c² in the rotary shaft C', upon which the type-sleeve is mounted. The rotary type-sleeve shaft C' has pivot-bearings c³ c⁴ on the frame of the machine, the pivot c³ being fixed in place by a set-screw c⁵. The 20 type-sleeve C is also provided with a series of registering notches c⁶ at each end, which fit the stop-pins D, with which they engage. The outer portions of these registering notches c⁶ are made inclined or cam-shaped at c⁷, so that 25 the registering notch c⁶ will readily engage the stop-pin and the latter serve to cause the type-sleeve to accurately register both longitudinally and radially with the line of printing and properly space the letters therein. 30 The type-sleeve C preferably has nine faces or rows of characters, with ten characters in each row or face, five being on each side of the annular groove c. The sliding or reciprocating movement of the type-sleeve C on its 35 shaft C' serves to bring the different characters in each row longitudinally into position in front of the impression-hammer, and the radial movement of the type-sleeve by the rotation of its shaft C' serves to bring each of 40 the characters radially into position in front of the impression-hammer. The key-levers B' of the first row of keys operate simply to slide the type-sleeve without rotating it, while the key-levers B² of the second row of keys 45 operate not only to slide the type-sleeve, but also to rotate it one-ninth of a revolution, and the key-levers B³ of the third row of keys operate to slide the type-sleeve and to rotate it one-ninth of a revolution in the opposite direction. 50 On the type-sleeve there are three different cases of type or characters, three rows or faces of the type-sleeve constituting one case of characters. To bring the second and third cases of characters on the type- 55 sleeve into the field of operation, two keys and key-levers are employed, one to rotate the type-sleeve one-third of a revolution, the other two-thirds of a revolution.

O is the key and O' the key-lever for the 60 cap-case of characters, and P and P' the key and key-lever for the figure-case of characters.

As the same sliding or longitudinal movement of the type-sleeve serves to move it into 65 proper position longitudinally for the characters of each of the three faces or rows of characters, the keys and key-levers are ar-

ranged in sets of three, one key of each set being found in each of the three rows of keys, and for the same reason the registering or stop pins D are ten in number, arranged five on each side of the machine or at each end of the type-sleeve. The two extreme stop-pins D may be fixed to the stationary frame-work of the machine; but the remaining eight—four on each 70 side—are necessarily movable, so that they may be moved into and out of position for engaging the registering notches at the ends of the type-sleeve. The necessary one-ninth rotary movement of the type-sleeve is communicated thereto from the key-levers B² of the second row of keys by means of a bar F, extending across all the key-levers B' B² B³, the key-levers B' and B³ being, however, notched or otherwise so constructed that they 75 will not engage or operate the cross-bar F, and the necessary one-ninth revolution of the type-sleeve C in the opposite direction is communicated thereto from the key-levers B³ of the third row of keys by a similar bar F', extending across the same, the key-levers B' and B² being of course notched, so that they 80 will not operate the bar F'. The necessary sliding or longitudinal movement is communicated to the type-sleeve C from each 85 of the ten sets of three contiguous key-levers B' B² B³ by a series of rock-shafts G, ten in number, each having an arm g, furnished with a foot g', which spans the three contiguous keys B' B² B³ of each set. Five of these 90 rock-shafts G are on each side of the machine, those on one side operating to move the type-sleeve from its middle or normal position in 95 one direction and those on the other side in the opposite direction. 100

It will be observed that the parts which I have thus far enumerated have substantially the same general construction and mode of operation as the corresponding parts of my former patents above mentioned.

The mechanism for communicating the necessary rotary movement to the type-sleeve C or its shaft C' consists of the intermeshing gears C² C³ and swinging segment gear or rack C⁴, mounted upon the pivot-bearing pin c⁴ of 115 the shaft C'. The intermediate gear C³ is journaled upon a swinging arm or lever C⁵, and the gear C² is connected directly to the type-sleeve shaft C'. The segment or rack C⁴ is operated by the case-key levers O' and 120 P' through the connecting-link P², having a pin p at its lower end, which engages the levers O' P'. The cap-lever O' serves to turn the segment C⁴ sufficiently to cause the type-sleeve to rotate one-third of a revolution and 125 the figure-lever P' sufficiently to cause the type-sleeve to rotate two-thirds of a revolution. The key-levers B² of the second row of keys communicate the necessary one-ninth 130 rotary movement to the type-sleeve through the cross-bar F, connecting-link f f, lever-arms h h, and rock-shaft H, one of the arms h of the rock-shaft having a cam h', which engages a pin k on the bent lever K, which is 135

connected by a link k' with the lever or arm C^5 , on which the gear C^3 is journaled. The necessary one-ninth rotary movement of the type-sleeve in the opposite direction is communicated thereto from the third row of keys B^3 through the bar F' , links f' , rock-shaft H' , having arms h^2 , one of said arms h^2 having a cam h^3 , which engages the pin k on the opposite side thereof from the lever-arm h , thus moving the arm C^5 in the opposite direction.

As shown in Fig. 9, the lever h is represented as being raised or partially raised by its link f , and thus in the act of causing its cam h^3 to actuate the bent lever K . It will be understood that the lever h returns to its normal position when the other lever h^2 and its cam h^3 are operating the bent lever K . The segment gear or rack C^4 is preferably constructed with a hub C^6 , upon which the gear C^2 and lever-arm C^5 are journaled. The connection between the gear C^2 and the type-sleeve shaft C' preferably consists of an arm c^8 on the shaft C' , which fits in a slotted disk c^9 , secured to the gear C^2 .

C^7 is a stop, which engages a stop-pin C^8 on the swinging arm C^5 to approximately limit the throw of said arm in either direction to insure the proper engagement of the registering notches c^6 on the type-sleeve with the stop-pins D .

The necessary longitudinal movement is communicated to the type-sleeve C from each set of three keys, as before stated, through the rock-shaft G , having arm g , furnished with foot g' . Each of these ten rock-shafts G is also furnished with an arm g^2 , which engages the horizontal cam-shaped lever J , the end of the lever J being curved or cam-shaped at j' and engaging a pin n on the upright lever N , the upper end of which is furnished with a pin n' , which engages the annular groove c in the type-sleeve. This upright lever N is made hook-shaped or curved, substantially as indicated in the drawings, so that it will not interfere with the lower web of the ink-ribbon. The series of arms g^2 on the rock-shafts G move the type-sleeve longitudinally different distances, according to their distance from the pivot j of the lever J . The stop-pins D are connected to and operated by the arms g^2 of the rock-shaft G .

M is the rock-shaft to which is secured the hammer-operating lever M' . This hammer-operating lever M' has feet or wings m , m' , which project over the arms g^2 on the rock-shaft G , so that the lever M' will receive motion therefrom. The lever M' , with its wings m , also serves as a returning-lever to return the stop-pins D and their operating-arms g^2 to their normal position after each impulse. This is done by a spring M'' , connected to a lever M^2 on the rock-shaft M , and which engages an arm m' , rigidly secured to the rock-shaft. The hammer-operating lever M' is also provided with a cross-bar or bridge m^2 , having inclined or cam-shaped faces m^3 , m^4 , terminating in a registering notch m^4 , which engages

the pin n on the lever N , which slides the type-sleeve, and thus serves to return the type-sleeve longitudinally to position after each impulse. The rock-shaft M is further provided with a returning arm or lever M^4 , having a double-inclined or cam-shaped notch m^5 , that engages the operating-pin k of the bent lever K , and thus serves to return it and the type-sleeve operated therefrom to position after each impulse.

The hammer-operating arm or lever M' is furnished at its extreme end with a pin or projection m^6 , which engages the hook-shaped or slotted arm r , through which motion is communicated to the hammer R . The pin m^6 has a pointed or conical end to insure the ready engagement of the same with the slotted arm r .

R' is the goose-neck frame or support upon which the hammer R is mounted. This goose-neck frame slides or reciprocates on suitable guides a on the frame of the machine. The hammer R is secured to a rock-shaft R^2 , which is journaled in suitable bearings R^3 on the upper limb of the goose-neck R' , and motion is communicated to this rock-shaft from the slotted arm r through the rock-shaft R^4 , arm R^5 , link R^6 , and arm R^7 . The slot r' of the hammer-operating arm r is widened at its outer portion r^2 , so that the hammer, when an impulse is imparted to it from the pin m^6 in the lever M' engaging the slotted arm r , will be free to rebound after striking the type-sleeve—that is to say, the pin m^6 on the lever M' imparts at the first portion of its stroke a forward or striking impulse to the hammer R , the momentum of the hammer after thus receiving the impulse carrying it forward until it impinges against the type-sleeve. When the hammer impinges against the type-sleeve, it is free to rebound, because at this time the pin m^6 on the lever M' is not in engagement with the edge of the widened slot r' in the operating-arm r . By this arrangement the hammer simply delivers a blow while freely suspended from its pivot and free to rebound. The hammer-head r^3 is detachably secured to the hammer R by means of a set-screw r^4 , so that it may be conveniently and quickly removed and replaced by another removable hammer-head when desired for different kinds of work. For most uses a hard-rubber hammer-head should be employed; but for making a great number of manifold copies a harder or metallic hammer-head is preferably used. The hammer-head r^3 is made star-shaped, so that it has a number—preferably five—of operating-faces r^5 . By thus making the hammer-head star-shaped with a number of operating-faces its durability is greatly increased. The central hole through the hammer-head, by which it is secured in place on the hammer by the set-screw r^4 , serves, owing to the star shape of the hammer-head, to fix it properly in place for all its faces.

By simply slipping the goose-neck R' out on its guides a the slotted operating-arm r is brought into engagement with the conical-

pointed pin m^6 on the hammer-operating lever M' . A set-screw R^8 serves to fix the goose-neck hammer-supporting frame in place in its extended position. When the machine is not in use or is being carried about, the goose-neck frame R' is simply telescoped or slipped back on its guides within the main frame A , so that the machine as a whole has then no additional width.

10 By employing a goose-neck frame or support for the hammer and communicating motion thereto around the goose-neck I am enabled to pass the paper between the upper and lower limbs of the goose-neck frame, and thus around the hammer or between the hammer and the machine proper, thus enabling me to dispense with the paper-storage cylinder or holder around which in my previous machine the paper was wrapped or wound.

15 Q and Q' are the inking-ribbon spools. The shafts Q^2 Q^3 are journaled on a portion A^5 of the main frame. The bridge portion A^5 of the main frame is secured in place by screws. This bridge portion A^5 of the frame has a depending standard A^6 , upon which is journaled the ratchet q , through which motion is communicated to the spools from the pawl q' on the hammer-operating lever M' . Pivoted to the depending arm or bracket A^6 on the bridge portion A^5 of the frame is a locking-pawl q^2 , which likewise engages the ratchet and serves to prevent any back motion thereof. This locking-pawl q^2 has a weighted arm q^3 to hold it in engagement with the ratchet-wheel q .

20 The shafts Q^2 Q^3 of the ribbon-spools are each furnished with a gear q^4 or q^5 , to one of which motion is communicated from the ratchet-wheel by a gear q^6 thereon, which meshes with an intermediate gear q^7 , journaled on a

25 swinging arm or lever q^8 , pivoted to the shaft of the ratchet-wheel. Secured to the gear q^7 is a smaller gear q^9 , that meshes with one or other of the gears on the spool-shafts Q^2 Q^3 , according as the lever q^8 is shifted forward or backward. The lever q^8 is furnished with a pin q^{10} , which engages a latch q^{11} to hold the lever q^8 in position. The ribbon q^{12} passes from one spool Q around the type-wheel C to the other spool Q' . By shifting the lever q^8 from one position to the other either spool may be driven, thus winding the ribbon first on one spool and then on the other. The shafts Q^2 Q^3 of the ribbon-spools are made long enough so that the spools may be slipped into different positions longitudinally thereon, and thus bring different strips or portions of the ribbon in line with the impression-hammer. By this adjustment of the ribbon-spools on their shafts, in connection with the winding or traveling movement of the ribbon, every portion of the ribbon may be utilized.

30 Back of the type-sleeve C , I provide a ribbon-guard Q^4 , having an opening Q^5 therein for the face of the hammer to strike through. This ribbon-guard serves to keep the paper from coming in contact with the ribbon except at a point where the hammer-head strikes

the same. The ribbon-guard Q^4 is furnished with a pointer Q^7 at its upper middle portion to indicate the point on the printed line 70 where the hammer strikes. This is of service in making corrections and in adjusting the paper-carriage to position for work. The ribbon-guard Q^4 is secured to a horizontal arm Q^8 , attached to a bracket Q^9 on the main frame. The bracket Q^9 is also furnished with a horizontal guide-arm Q^{10} to support the ribbon-guard at its lower edge and prevent the same coming in contact with the type-sleeve. This horizontal arm Q^{10} is also of service as a 80 guide for the ribbon.

T is the paper-carriage. It slides on suitable guides a^3 a^8 on the frame of the machine, the guides or the carriage being furnished with friction-rolls t to cause the carriage to move 85 easily. The carriage is furnished with a rack T' , which engages the escapement mechanism. Pivoted to the carriage is a swinging frame T^2 , upon which the paper-feed roller T^3 is journaled. The shaft T^4 of the paper-feed 90 roller is furnished with a thumb-piece or hand-wheel T^5 at one end, by which the feed-roller may be turned by hand to adjust the paper in position when desired. At its opposite end the paper-feed roller is provided with a ratchet-wheel t' and a gear-wheel t^2 . The gear-wheel t^2 meshes with a gear t^3 , secured to the ratchet-wheel t' , which is operated by a pawl t^5 , pivoted to the pawl-lever t^6 . The pawl-lever t^6 also has a pawl or tooth t^7 , which engages the locking-ratchet t' on the paper-feed- 95 roll shaft. The pivotal or swinging arm T^2 is provided with a graduated series of holes t^8 , in which fits a stop-pin t^9 , that serves to limit the throw of pawl-lever t^6 , and thus 100 the extent of feed of the paper. By adjusting the stop-pin t^9 to different positions the space between the lines may be regulated, as desired. The stop-pin t^9 is mounted in a swinging arm or bearing t^{10} , pivoted to the 105 shaft t^{11} , upon which the pawl-lever swings. The pivotal or swinging frame T^2 , that carries the paper-roller, is also provided with a curved shield or paper-guide T^6 , upon which is journaled a small friction-roller T^7 , between 110 which and the feed-roller the paper passes. This serves to insure a better and more convenient feed of the paper. The curved shield T^6 is provided with a slot or opening for the friction-roll T^7 to project through and with a curved lip T^8 . The curved shield T^6 is provided with lips T^9 , by which it is pivotally secured to the swinging frame T^2 by pivots or screws T^{10} , and adjusting-screws T^{11} , connected by springs T^{12} with the shield T^6 near its upper edge, serve to adjust or regulate the pressure of the shield and its friction-roll T^7 against the paper-feed roll T^3 . For 115 convenience in inserting the paper and also to keep the paper from the mechanism below, the paper-carriage T is furnished with a bottom plate or guard T^{13} .

The paper-carriage is actuated in the usual manner by a main spring in the drum t^{12}

through the connecting-cord t^3 . The paper-carriage T is provided with an erasing-plate T^{14} to form a smooth and firm support for the paper, and thus enable erasures and corrections to be made without removing the paper from the machine. The pivotal or swinging frame T^2 is likewise provided with a bar T^{15} , having a handle T^{16} at its end. This bar T^{15} swings past the erasing-plate, and thus permits the paper to lie down against the plate. This bar T^{15} also serves as a guard for the paper to prevent it lapsing backward over the hammer.

The escapement mechanism is substantially the same as in my previously-patented machine, and consists, briefly, of a shaft S, carrying a gear T^{17} , which meshes with the rack T' on the paper-carriage T. The escapement-shaft S is furnished with a sleeve S' and a ratchet-wheel s' and a clutch s². The shaft S is also furnished with a sliding clutch s³, held in place by a spring s⁴, which engages the clutch s². The shaft S is also furnished with a sleeve s⁵ and a pin or crown wheel s⁶, having a slot s⁷, through which a pin s⁸ on the ratchet-wheel s' before mentioned projects. A spring s⁹ connects the pin s⁸ to the pin s¹⁰ on the back of the ratchet-wheel s'. The sliding clutch s³ is actuated by a bent or thumb lever S³, which is held in place by a spring S³. The pin or crown wheel s⁶ is engaged by the pawl-lever M² on the rock-shaft M. The pawl-lever M² is operated from the keys through the rock-shaft M, lever M', and rock-shaft G in the manner hereinbefore explained. The pawl-lever M² is operated directly from the spacing-key V and lever V' by the connecting-link V².

Pivoted to the main frame at P⁴ is a locking latch or pawl P⁵, which serves when pushed in one direction to engage and hold the cap-key lever O' in its depressed or operating position and when pushed in the opposite direction to hold the figure-key and key-lever P P' in their depressed or operating position.

Y is the bell, which is operated in the usual manner when the carriage T reaches the limit of its movement.

O² is the stop for the lever O', and P⁷ the stop for the lever P'.

P⁶ is the spring for returning the levers O' and P' to position.

The lever M⁴ is provided with a pin m⁷, which spans the lever-arms h h², and thus serves to return said lever-arms to place.

I claim—

1. In a type-writer having a type wheel or sleeve and an impression-hammer, the combination, with the impression-hammer, of a rock-shaft R² for operating said hammer and a goose-neck frame or support upon which said rock-shaft is journaled, so that the paper may pass around the hammer or between it and the machine proper, substantially as specified.

2. In a type-writer, the combination, with

the main frame, of a telescopic or sliding goose-neck frame and an impression-hammer mounted upon said sliding goose-neck, substantially as set forth.

3. In a type-writer having a type wheel or sleeve and an impression-hammer, the combination, with the impression-hammer, of a rock-shaft for operating said hammer, a second rock-shaft for communicating motion to said first-mentioned rock-shaft, and a goose-neck frame or support, upon each of the two limbs of which one of said rock-shafts is journaled, so that the paper may pass around the hammer or between it and the machine proper, substantially as specified.

4. In a type-writer having a type wheel or sleeve and an impression-hammer, a star-shaped hammer-head having a series of operating-faces, substantially as specified.

5. In a type-writer having a rotatable sliding type-sleeve, the mechanism for rotating the type-sleeve, consisting in the gears C² C³ and swinging segment gear or rack C⁴, said gear C³ being mounted upon a swinging arm 90 or lever C⁵, substantially as specified.

6. The paper-carriage T, furnished with pivotal or swinging frame T², carrying feed-roll T³, and curved guard or shield T⁶, pivoted to said swinging frame T² and furnished with adjusting-screws T¹¹ and springs T¹², substantially as specified.

7. The combination of the paper-carriage having erasing-plate T¹⁴ and furnished with swinging frame T², upon which the paper-feed roll is mounted, said swinging frame serving to impose the paper on said erasing-plate when the swinging frame is turned up, substantially as specified.

8. The combination of the paper-carriage having erasing-plate T¹⁴ and furnished with swinging frame T², upon which the paper-feed roll is mounted, said swinging frame serving to impose the paper on said erasing-plate when the swinging frame is turned up, said swinging frame being provided with a curved guard or shield T⁶, substantially as specified.

9. The combination, with paper-carriage T, of swinging frame T², feed-roll T³, having shaft T⁴, provided with ratchet-wheel t', gear-wheel t², pawl-lever t⁶, furnished with pivoted pawl t⁵ and pawl-tooth t⁷, gear t⁸, and ratchet-wheel t⁴, all combined and operating substantially as specified.

10. The combination, with paper-carriage T, of swinging frame T², feed-roll T³, having shaft T⁴, provided with ratchet-wheel t', gear-wheel t², pawl-lever t⁶, furnished with pivoted pawl t⁵ and pawl-tooth t⁷, gear t⁸, and ratchet-wheel t⁴, said swinging frame T² being provided with graduated holes t⁹ and stop-pin t¹⁰ to limit the throw of said pawl-lever t⁶, substantially as specified.

11. The combination of paper-carriage T with a swinging frame T², paper-feed roll T³, curved guard T⁶, having lips T⁹, by which it is secured to said frame T², and adjusting-

screws T¹¹ for regulating the pressure between said feed-roll T³ and the upper edge of said curved guard T⁶, substantially as specified.

12. The combination of paper-carriage T, having erasing-plate T¹⁴, with swinging frame T², carrying the paper-feed roll T³ and provided with guide-bar T¹⁵, adapted to swing past said erasing-plate, substantially as specified.

13. The combination, in a type-writer, of a type-sleeve, an impression-hammer, a lever, as M', for operating the impression-hammer, and a slotted arm r for communicating motion from said operating-lever M' to the hammer, the slot of said arm having a widened portion to permit the hammer to freely rebound from the type-sleeve after receiving an impulse, substantially as specified.

14. The combination of a type-sleeve with a swinging impression-hammer R, a lever M' for operating the same, a slotted arm r, and mechanism for connecting said arm r with the hammer, substantially as specified.

15. The combination of hammer-operating arm M' with hammer R, slotted arm r, goose-neck frame or support R' for said hammer, rock-shaft R⁴, arm R⁵, link R⁶, arm R⁷, and rock-shaft R², upon which the hammer is secured, substantially as specified.

16. The combination, in a type-writer, of the main frame with a hammer-operating lever M' mounted thereon, a sliding goose-neck frame R', hammer R, mounted on said goose-neck, rock-shaft R², arm R⁷, link R⁶, arm R⁵, rock-shaft R⁴, and slotted arm r, connected with said lever M' by a pin m⁶, so that the act of sliding the goose-neck frame out or in connects or disconnects the hammer-operating mechanism on the main frame with or from that on the goose-neck frame, substantially as specified.

17. In a type-writer, the combination, with a rotary type sleeve or wheel, of a gear on its shaft for revolving the same and two swinging arms, one carrying a segment gear or rack and the other an intermediate gear meshing with said rack and with said gear on said type-wheel shaft, one of said swinging arms being connected to and operated by the key-levers and the other being connected to and operated by the lever or levers for changing the case of type to be operated by the key-levers, substantially as specified.

18. The combination of rotary type-sleeve C, its shaft C', a gear C², connected therewith, a swinging arm C⁵, carrying gear C³, and swinging segment gear or rack C⁴, the key-levers, and a case-changing key-lever, mechanism connecting said segment-gear C⁴ with said case-changing lever, and mechanism connecting said swinging arm C⁵ with the key-levers, substantially as specified.

19. The combination of the rotary sliding type-sleeve C, its shaft C', gear C², gear C³, swinging segment-gear C⁴, swinging arm C⁵, mechanism for operating said swinging arm

C⁵ from the key-levers, and a stop C⁷ and stoppin C⁸ to limit the throw of said arm C⁵, substantially as specified.

20. The combination of a rotary sliding type-sleeve C, its shaft C', gear C², intermediate gear C³, segment-gear C⁴, swinging arm C⁵, lever K, connected to said swinging arm C⁵, and rock-shaft H, having lever-arm h, furnished with cam h', engaging a pin on said lever K, substantially as specified.

21. The combination of a rotary sliding type-sleeve C, its shaft C', gear C², intermediate gear C³, segment-gear C⁴, swinging arm C⁵, lever K, connected to said swinging arm C⁵, rock-shaft H, having lever-arm h, furnished with cam h', engaging a pin on said lever K, rock-shaft H', having arm h², furnished with cam h³, likewise adapted to engage the pin on said lever K, rock-shaft M, furnished with lever-arm M⁴, having double-inclined or cam-shaped notch m⁵, and a spring for turning said rock-shaft M, substantially as specified.

22. The combination of the rotary type-sleeve, its shaft C', gear C², intermediate gear C³, swinging segment gear or rack C⁴, swinging arm C⁵, carrying said gear C³, mechanism for operating said swinging arm from the key-levers, a case-changing key and lever O O', a link connecting said lever O' with said segment-gear C⁴, and a stop O² for limiting the movement of said lever O', substantially as specified.

23. The combination of rotary sliding type-sleeve C, its shaft C', gear C², intermediate gear C³, swinging segment-gear C⁴, swinging arm C⁵, the key-levers, and mechanism connecting said key-levers with said swinging arm C⁵, case-changing keys and levers O O' P P', link P², connecting said levers O' P' with said segment C⁴, a spring P⁶ for returning the same, and stops O² and P⁷ for limiting the movement of said levers O' and P', substantially as specified.

24. The combination of rotary sliding type-sleeve C, its shaft C', gear C², intermediate gear C³, swinging segment-gear C⁴, swinging arm C⁵, the key-levers, and mechanism connecting said key-levers with said swinging arm C⁵, case-changing key and levers O O' P P', link P², connecting said levers O' P' with said segment C⁴, a spring P⁶ for returning the same, stops O² and P⁷ for limiting the movement of said levers O' P', and a pivoted latch P⁵, adapted to engage said levers O' and P' to hold the same in their depressed position, substantially as specified.

25. The combination, with sliding type-sleeve C, having annular groove e, of lever N, having pins n n', horizontal levers J J, having cam-shaped ends engaging said pin n, and spring-actuated lever M', furnished with cross-bar m², having cam-shaped faces m³ m³, terminating in a registering notch m⁴, adapted to engage said pin n on the lever N, substantially as specified.

26. The combination, with a rotary sliding

type-sleeve C, of the keys B, key-levers B' B² B³, cross-bars F F', links f f', rock-shafts H H', having arms h h², furnished with cams h' h³, lever K, having pin k, link k', swinging arm C⁵, carrying gear C³, segment-gear C⁴, gear C² on said type-sleeve shaft, and rock-shaft M, having arm M⁴, furnished with notch m⁵, engaging said pin k on said lever K, substantially as specified.

- 10 27. The combination, with a rotary sliding type-sleeve C, of the keys B, key-levers B' B² B³, cross-bars F F', links f f', rock-shafts H H', having arms h h², furnished with cams h' h³, lever K, having pin k, link k', swinging arm C⁵, carrying gear C³, segment-gear C⁴, gear C² on said type-sleeve shaft, and rock-shaft M, having arm M⁴, furnished with notch m⁵, engaging said pin k on said lever K, rock-shafts G, having lever-arms g, furnished with feet g', spanning each three of said key-levers, one in each row, and furnished with arms g², stop-pins D, operated thereby, horizontal levers J J, having cam-shaped ends, upright lever N, having pins n n', engaging, respectively, said 20 levers J and the type-sleeve C, rock-shaft M, and lever M', furnished with wings m, spanning said lever g², substantially as specified.
- 25 28. The combination, with a rotary sliding type-sleeve C, of keys B, key-levers B' B² B³, cross-bars F F', links f f', rock-shafts H H', having arms h h², furnished with cams h' h³, lever K, having pin k, link k', swinging arm C⁵, carrying gear C³, segment-gear C⁴, gear C² on said type-sleeve shaft, rock-shaft M, having arm M⁴, furnished with notch m⁵, engaging said pin k on said lever K, rock-shafts G, having lever-arms g, furnished with feet g', spanning each three of said key-levers, one in each row, and furnished with arms g², stop-pins D, operated thereby, horizontal levers J J, having cam-shaped ends, upright lever N, having pins n n', engaging, respectively, said 30 levers J and the type-sleeve C, rock-shaft M, and lever M', furnished with wings m, spanning said lever g², substantially as specified.
- 35 40 45 28. The combination, with a rotary sliding type-sleeve C, of keys B, key-levers B' B² B³, cross-bars F F', links f f', rock-shafts H H', having arms h h², furnished with cams h' h³, lever K, having pin k, link k', swinging arm C⁵, carrying gear C³, segment-gear C⁴, gear C² on said type-sleeve shaft, rock-shaft M, having arm M⁴, furnished with notch m⁵, engaging said pin k on said lever K, rock-shafts G, having lever-arms g, furnished with feet g', spanning each three of said key-levers, one in each row, and furnished with arms g², stop-pins D, operated thereby, horizontal levers J J, having cam-shaped ends, upright lever N, having pins n n', engaging, respectively, said levers J and the type-sleeve C, rock-shaft M, lever M', furnished with wings m, spanning said levers g², hammer R, and mechanism connecting said lever M' with said hammer, substantially as specified.

29. The combination, with a rotary sliding type-sleeve C, of keys B, key-levers B' B² B³, cross-bars F F', links f f', rock-shafts H H', having arms h h², furnished with cams h' h³, lever K, having pin k, link k', swinging arm C⁵, carrying gear C³, segment-gear C⁴, gear C² on said type-sleeve shaft, rock-shaft M, having arm M⁴, furnished with notch m⁵, engaging said pin k on said lever K, rock-shafts G, having lever-arms g, furnished with feet g', spanning each three of said key-levers, one in each row, and furnished with arms g², stop-pins D, operated thereby, horizontal levers J J, having cam-shaped ends, upright lever N, having pins n n', engaging, respectively, said levers J and the type-sleeve C, rock-shaft M, lever M', furnished with wings m, spanning said levers g², hammer R, and mechanism connecting said lever M' with said hammer, the ribbon-spools, and the pawl-and-ratchet mechanism for operating the ribbon-spools, the pawl of said mechanism being carried by said lever M', substantially as specified.

30. The combination, with the keys and levers, of the rock-shaft G, having arms g, furnished with feet g', spanning the key-levers, and arms g², rock-shaft M, having hammer-operating lever M', furnished with feet m, spanning said arms g², the hammer R, and mechanism connecting the hammer with said lever M', substantially as specified.

35 40 45 30. The combination, with the keys and levers, of the rock-shaft G, having arms g, furnished with feet g', spanning the key-levers, and arms g², rock-shaft M, having hammer-operating lever M', furnished with feet m, spanning said arms g², the hammer R, and mechanism connecting the hammer with said lever M', substantially as specified.

SAMUEL J. SEIFRIED.
